UNITED STATES PATENT OFFICE.

ALBERT BROWN, OF MENDOCINO, CALIFORNIA.

COMBINED PAPER CUTTER AND STAMPER.

SPECIFICATION forming part of Letters Patent No. 341,446, dated May 11, 1886.

Application filed August 30, 1884. Serial No. 141,873. (No model.)

To all whom it may concern:

Be it known that I, ALBERT BROWN, a citizen of the United States, residing at Mendocino, in the county of Mendocino and State of California, have invented a new and useful Improvement in Combined Paper Cutter and Stamper, of which the following is a specification, reference being had to the accompanying drawings.

10 My invention relates to a combined paper cutter and stamper; and it consists in the improved construction and combination of parts, hereinafter fully described and claimed.

In the drawings, Figure 1 is a view in perspective of a combined paper cutter and stamper constructed in accordance with my invention, and showing the roll of paper connected thereto. Fig. 2 is a vertical longitudinal section of the cutter and stamper. Fig. 3 20 is a horizontal section. Fig. 4 is a detail view of a modified form of inking-pad.

In the accompanying drawings, in which like letters of reference indicate corresponding parts in all the figures, A represents the cutter having its front side beveled, as shown, and provided on its under side with a narrow strip of sheet metal, a. Upon the ends of the cutter, near the upper corners thereof, is provided an outwardly-extending headed pin or 30 screw, b.

B represents the frame for supporting the roll of paper. This frame is preferably constructed of wire, and consists of the sides a' and ends a''. Extending upwardly from each 35 end of the frame are wires b', which converge and are looped at their upper ends.

B' represents the roll carrying the paper. The ends of this block or roll are provided with openings at their ends. Seated in said 40 openings are the ends of springs C, which pass through the loops of the wire supporting frame B, and are supported thereby. These springs are bent upwardly from their point of attachment to the cutter, and are then coiled, as 45 shown at c, from which point they extend to the roll carrying the paper, as above mentioned. The under side of the cutter is recessed or cut away to form an enlarged opening, D, communicating with which is an elongated slot, e, upon the upper side of the cutter. Secured to the upper side of this metal

plate is a bracket, which in form is substantially the shape of an inverted U, the only difference being that its upper end is flattened.

The plate E and bracket F are each provided 55 with registering holes or openings f. Working in said holes or openings of the said plate and bracket are two rods, g, connected at their upper ends by a cross piece or strip, h.

G represents coil-springs, which are mounted 60 on said rods between the plate E and the underside of the bracket F. It will be seen that when said bars are depressed by means of the cross piece or strip connecting them at their upper ends the tendency of the coil-springs 65 will be to force them upward. The ends of these rods extend through the slot or opening in the cutter, and mounted on their lower ends is a block or strip, i, carrying the stamp. This block or strip may be constructed of metal; or, 70 if desired, it may be constructed of wood or other suitable material and have a rubber stamp secured thereto. The sides of the enlarged hole or opening are cut away to form a dovetailed recess near one end, (the end occupied by the stamper when in its normal position, as shown in Fig. 1.) Fitting said dovetailed recess is an inking-pad, which consists of a strip of wood which is adapted to entirely 75 close one end of the enlarged opening, said 80 strip carrying the pad on its upper side. The pad is let into the strip, so that it will be flush therewith.

In Fig. 4 I have shown another form of pad, which consists of a shallow pan having a strip, 85 b³, secured to its under side, said strip being somewhat larger than the pan itself, and is adapted to be secured to the cutter by screws or other suitable means.

It will be seen that to ink the stamp it is only 90 necessary to depress the same so that it will come in contact with the pad.

At the opposite end of the cutter from that occupied by the inking-pad there is provided a chamber, j, which communicates with the 95 enlarged opening, and extends nearly the entire length of the cutter from the end of said opening. In this opening is mounted a spiral spring, k. Fitting in said chamber is a pusher, k', which bears against the said coil-spring. 100 The forward end of said presser or shaft is provided with a cross piece or block, which

bears against the strip carrying the stamp, and holds said stamp at the opposite end of the enlarged opening directly over the inking-pad.

When it is desired to stamp the paper, the bracket to which the inking-pad is connected is moved to the opposite end of the elongated slot, thus withdrawing the stamp from the pad, and at the same time pushing the presser-shaft into the chamber *j*. As soon as the stamp has cleared the inking-pad it may be depressed to mark the paper.

Having fully described my invention, what I claim as new, and desire to secure by Letters Patent, is—

15 1. The combination, with the cutter having an enlarged opening on its under side and a slot communicating therewith, as described, of a bracket secured to a plate, said bracket and plate having holes or openings, rods or 20 shafts mounted in the openings of said bracket and plate, and coil-springs mounted on said

rods or shafts between the bracket and plate, said shafts carrying a stamp at their lower ends and connected at their upper ends, substantially as set forth.

2. The combination, with the cutter having an enlarged opening on its under side and having a slot communicating with said opening, of a sliding stamp held normally in position at one end of the opening by a spring-actuated pusher, and carrying a plate to close slot *e*, and the pad located below the stamp, said pusher, pad, and plate closing the space in which the stamp is located, and preventing the access of dust thereto, as set forth.

In testimony that I claim the foregoing as my own I have hereto affixed my signature in presence of two witnesses.

ALBERT BROWN.
